[57] **CLAIM**

The ornamental design for a combined toothbrush and cover therefor, as shown and described.

DESCRIPTION

FIG. 1 is a side elevational view of a combined toothbrush and cover therefor showing my new design, the opposite side being a mirror image thereof;

FIG. 2 is a front elevational view, the rear being a mirror image thereof;

FIG. 3 is an end elevational view as seen from the bottom of FIG. 1;

FIG. 4 is an elevational view of the opposite end thereof;

FIG. 5 is a front elevational view thereof with the cover removed for clarity of illustration;

FIG. 6 is a side elevational view, the opposite side being a mirror image thereof;

FIG. 7 is a rear elevational view thereof;

FIG. 8 is an end elevational view as seen from the bottom of FIG. 6; and

FIG. 9 is an elevational view of the opposite end thereof.
